US0D1107577S

(12) **United States Design Patent** (10) Patent No.: **US D1,107,577 S**
(45) Date of Patent: ** Dec. 30, 2025

(54) **PRESSURE TRANSMITTER**

- (71) Applicant: **Yokogawa Electric Corporation**,
Tokyo (JP)
- (72) Inventors: **Hiroki Yamawaki**, Musashino (JP);
Toshiya Tsukiai, Musashino (JP);
Taihei Hamada, Musashino (JP);
Naoto Takano, Musashino (JP); **Taku Koizumi**, Musashino (JP)
- (**) Term: **15 Years**
- (21) Appl. No.: **35/522,758**
- (22) Filed: **Oct. 25, 2023**

(80) **Hague Agreement Data**

Int. Filing Date: **Oct. 25, 2023**
Int. Reg. No.: **DM/233454**
Int. Reg. Date: **Oct. 25, 2023**
Int. Reg. Pub. Date: **Oct. 25, 2024**

(51) **LOC (15) Cl.** **10-04**
(52) **U.S. Cl.** **D10/85**

Primary Examiner — Antoine Duval Davis

CLAIM

The ornamental design for pressure transmitter as shown and described.

DESCRIPTION

1. Pressure transmitter

- 1.1 : Perspective
1.2 : Front
1.3 : Back
1.4 : Top
1.5 : Bottom
1.6 : Left
1.7 : Right

The broken lines do not form part of the claimed design.

1 Claim, 7 Drawing Sheets
